CIRCUIT-ARRANGEMENT FOR TONE-CONTROL IN LOW-FREQUENCY AMPLIFIERS

Henricus Adrianus Broos, Eindhoven, Netherlands, assignor to Hartford National Bank and Trust Company, Hartford, Conn., as trustee

Application June 21, 1949, Serial No. 100,438
In the Netherlands June 25, 1948

3 Claims. (Cl. 179—171)

1

My copending U. S. patent application, Serial No. 790,102, filed December 6, 1947, now Patent No. 2,547,739, issued April 3, 1951, describes a tone control circuit for a low frequency amplifier wherein a negative feedback voltage, derived from a potentiometer and varying in frequency in accordance with the position of the movable contact of the potentiometer, is applied to the grid circuit of at least one of the amplifying tubes of the amplifier. In one of the circuit arrangements described in my said patent application, a negative feedback voltage for the middle frequency range is applied to a second fixed contact of the potentiometer and a negative feedback potential for the high frequency range is applied to a movable contact of the potentiometer, a third fixed contact of the potentiometer being coupled to the grid of the amplifier tube.

The principal object of the present invention is to provide an improved tone control circuit arrangement.

More particularly, it is an object of the invention to provide a simplified and more efficient tone control circuit of the type described in my said copending patent application.

Another object of the invention is to provide a tone control circuit which may be used advantageously in combination with a physiological tone control.

Further objects of the invention will appear from the following description.

The present invention is based on recognition of the fact that a low-frequency amplifier arrangement, more particularly an arrangement used in the low-frequency amplifying stage of a wireless receiving set, frequently comprises separate negative feedbacks or other means operative to bring about an attenuation of the intermediate tones relatively to the low and high tone frequencies. More particularly, such a negative feedback of the intermediate tone frequencies is found if a physiological control is provided in the receiver, that is to say a control in which, if the amplifier is adjusted for a high gain by use of a volume control, the low tone frequencies are amplified to a smaller extent relatively to the intermediate and high tone frequencies than if the volume control is adjusted for a low amplifier gain. In such an amplifier the invention permits simplification of the tone-control circuit-arrangement, and in particular the intermediate tone frequency filter.

According to the invention, the intermediate tone frequencies are attenuated in the preceding channel of the low-frequency amplifier relatively

2

to the low and high tone frequencies. In this case it is not necessary to provide an intermediate tone filter between the source of output voltage and the potentiometer. Instead, it is merely necessary to intercouple one of the contacts of the potentiometer and ground through a filter adapted to pass the intermediate and high tone frequencies.

In order that the invention may be more clearly understood and readily carried into effect, one form will now be described more fully by way of example with reference to the accompanying drawing, which is a schematic circuit diagram.

Referring now to the drawing, a low frequency amplifier is shown in the upper right hand corner thereof. This amplifier comprises an electron discharge tube 3. A second electron discharge tube is coupled in cascade with tube 3. To the anode circuit of this second tube there is coupled an output transformer 4. The grid circuit of tube 3 comprises a potentiometer 5 having fixed contacts *a*, *b* and *c* and a movable contact. Fixed contact *a* is coupled to a point A on the secondary winding of transformer 4 through a filter including resistor 6 and a capacitor 7.

This filter is adapted to pass low frequencies and serves to apply a negative feedback potential for the low frequency range to the point *a* of potentiometer 5. Conductor 1 serves to interconnect the fixed contact *c* and the grid of tube 3. The movable contact of potentiometer 5 is coupled to the secondary winding of output transformer 4 through a capacitor 14. Capacitor 14, the value of which is selected so as to pass solely the high frequency range, serves to apply a negative feedback voltage for the high frequency range to the potentiometer 5. Capacitor 14 is shown in the drawing as being connected to point A of output transformer 4. However, capacitor 14 might be connected to some other point on the output transformer, such as point E.

The arrangement thus far described provides a large negative feedback voltage for the high frequency range when the moving contact of the potentiometer 5 is located in the vicinity of fixed contact *c*. If the movable contact of the potentiometer 5 is located near the fixed contact *a*, the high frequency negative feedback voltage is sharply reduced. Adjustment of the movable contact to the fixed contact *a* is therefore suitable for reproduction of speech, whereas adjustment to the point *c* is suitable for the reproduction of music.

The influencing of the intermediate tone fre-

quencies is brought about, according to the invention, in that in the channel preceding the amplifying tube 3, comprising blocking resistance 15, a high negative feedback for the intermediate tone frequencies is effective, for example, in that a voltage which is proportional to the output voltage is supplied, through an intermediate tone filter, to the grid circuit of a discharge tube. In addition, the fixed contact *b* of potentiometer 5 is connected through a capacitor 20 to a point of constant potential, in this case ground. Capacitor 20, constitutes a filter adapted to pass at least the intermediate and high tone frequencies. The value of capacitor 20 may be, for example, between .05 and .1 F.

Since in the preceding stage a high degree of negative feedback of the intermediate tone frequencies occurs, the oscillations supplied through the conductor 1 to the amplifying tube 3 will have an attenuation of the intermediate tones relatively to the low and the high tones. Since, in the grid circuit of the amplifying tube 3 a frequency-dependent negative feedback voltage appears, the frequency relationship of which is determined by the position of the sliding contact of the potentiometer 5, the final amplifying characteristic curve is such that, if the sliding contact is located in the proximity of the fixed contact *a* of the potentiometer, both the low and the intermediate tone frequencies are negatively fed back (speech position), whereas, if the said sliding contact is in the proximity of the fixed contact *c*, both the intermediate and the high tone frequencies are negatively fed back (mellow position). If the sliding contact of the potentiometer 5 is located in the proximity of the fixed contact *b*, which is connected to earth through the condenser 20, a negative feedback of the high tone frequencies will no longer take place, since the impedance of the condenser 20 is low relatively to the condenser 14, which permits passage of only high tone frequencies. At the same time a negative feedback of the low tone frequencies is reduced to a marked extent, since the negative feedback voltage operative across the condenser 1 is divided as to voltage as far as the low tone frequencies are concerned across the impedance of the part of the potentiometer 5 which is intermediate the contacts *a* and *b* of the potentiometer and those of condenser 20. The arrangement is thus materially simplified without any loss of the advantages which permits the tone setting to be adjusted continuously from that for speech reproduction to music reproduction and mellow reproduction without the amplification of the intermediate-tone range, to which the human ear is most sensitive being modified due to the tone control.

The circuit-arrangement according to the invention may be used with particular advantage in conjunction with the so-called physiological tone control described in my copending U. S. patent application Ser. No. 17,243, filed March 26, 1948, now Patent No. 2,569,973, issued October 2, 1951.

To illustrate application of the invention to a circuit arrangement employing physiological tone control, the grid circuit of amplifying tube 3 is provided with a voltage obtained from the sliding contact 26 of the gain control 24, to the top 31 of which the low-frequency oscillations yielded in the output of a detector stage including an input circuit 21, a diode tube 22, and

an output network 23, 25 are supplied through a resistance 23 and whose lower end 31 is connected to a source of negative feedback voltage, for example, the tapping B of the output transformer 4 of the amplifying circuit arrangement. With the use of resistances 34 and 40, the top 31 of the gain control 24 also has supplied to it a positive feedback voltage obtained from the tapping D of the output transformer 4, so that at this point substantially no negative feedback is effective. Capacitor 33 and resistor 34 which intercouple point 32 of potentiometer 24 and the point D of output transformer 4 and capacitor 35 and resistor 36 which intercouple point 32 of potentiometer 24 and point B of output transformer 4 serve as intermediate frequency tone filters. These filters insure that, if the movable contact 26 of gain control 24 is moved downwards, corresponding to a decrease in gain of the circuit arrangement, the negative feedback for the intermediate tone frequencies is increased. Since an amplifier comprising the physiological tone control comprises the circuit elements 33, 34, 35 and 36, combination of such an arrangement with the circuit of the invention combines the advantages of the invention with a physiological tone control with a minimum of circuit elements.

While my invention has been described in a particular use thereof and in a particular embodiment, I do not wish to be limited thereto, for obvious modifications thereof will occur to those skilled in the art without departing from the spirit and scope of my invention.

What I claim is:

1. A circuit arrangement for amplifying an incoming signal voltage having frequency components within a given range, said arrangement comprising a physiological gain control network having a frequency response characteristic within said given range at which the intermediate frequency portion thereof is attenuated relative to the high and low-frequency portions thereof, first and second electronic amplifier stages each having an electron discharge tube provided with a cathode, a grid and an anode, and a grid input and an anode output circuit, the output circuit of said first stage being coupled to the input circuit of the second stage, means to supply said signal voltage through said network to the input circuit of said first stage whereby an output voltage is produced across the output circuit of said second stage, and apparatus to vary the frequency response of said arrangement, said apparatus including first, second and third frequency selective circuit means coupled to the output circuit of said second stage to derive respectively from said output voltage a low-frequency negative feedback voltage, an intermediate frequency negative feedback voltage and a high-frequency negative feedback voltage, means to apply said intermediate frequency voltage to said network to vary the intermediate frequency attenuation thereof, a potentiometer provided with first, second, third and fourth contacts, said fourth contact being movable, one of said third and fourth contacts being connected to the grid of the first stage, the first contact being coupled to the cathode of said first stage, means to apply said low-frequency voltage to said first contact, means to apply said high-frequency voltage to the other of said third and fourth contacts and means having a low impedance value at intermediate and high-frequencies relative to its value at low-frequencies connecting said second contact to a point of

ground potential whereby movement of said fourth contact along said potentiometer varies the frequency response of said circuit arrangement.

2. A circuit arrangement as set forth in claim 1 wherein said one of said third and fourth contacts is the third contact, and said means connecting said second contact to a point of ground potential includes a capacitance.

3. A circuit arrangement as set forth in claim 1 wherein said one of said third and fourth contacts is the fourth contact.

HENRICUS ADRIANUS BROOS.
